FREEZING TRAY WITH ICE RELEASE

Logan L. Mallard, Norfolk, Va.

Application December 4, 1941, Serial No. 421,642

8 Claims. (Cl. 62—108.5)

This invention relates to refrigeration and more particularly to freezing trays for use in the evaporator or freezing unit of a domestic refrigerator.

An object of the invention is to provide a tray of the type specified having rounded or circular freezing compartments and improved means coacting therewith for dislodging frozen or congealed matter from said compartments.

Another object is to provide a tray for making ice cubes having a simplified form of ice dislodging means operatively associated therewith but separable from the tray to adapt the latter for making ice cubes and for ordinary baking or other purposes.

Due to the lack of certain metals, it has been found necessary in certain instances to sell refrigerators without complete equipment, and another object of the present invention is to provide means rendering it possible to improvise a satisfactory ice mold or tray from an ordinary baking pan having rounded or circular compartments, such as the conventional muffin or cupcake pan and which can be purchased at a nominal cost in the open market.

A further object of the invention is to provide a freezing tray and coacting ice dislodging mechanism so constructed and arranged as to dislodge the ice mass by a simple yet powerful leverage action, after which the mechanism may be swung clear of the freezing compartments to permit free and unimpeded removal of the ice blocks or cubes.

The foregoing and other objects and advantages will become apparent in view of the following description taken in conjunction with the drawing, wherein:

Fig. 1 is a top plan view of a freezing tray and coacting ice-dislodging means constructed in accordance with the invention;

Fig. 2 is a view in section and side elevation of Fig. 1;

Fig. 3 is an elevation of the tray of Figs. 1 and 2, illustrating the ice-dislodging means swinging clear of the tray and the latter inverted to drop out the ice blocks or cubes;

Fig. 4 is a detail fragmentary view particularly illustrating a lever-hinging and mounting bracket forming part of the ice-dislodging means.

Referring to the drawing in detail, the tray comprises a frame 10 having therein parallel rows of rounded cup-shaped freezing compartments 11. This tray resembles the conventional baking pan for making cup cakes, muffins or the like, and in fact the ice-dislodging means to be de-

scribed is particularly adapted for such type of pan.

The ice-dislodging means in the form illustrated comprises an actuator bar 12 having connected thereto or formed integrally therewith a series of rigid downwardly projecting prongs or fingers 13, the latter being extended into the freezing chambers 11 to be embedded in the ice mass when the latter is frozen. One end of the bar 12 is mounted for longitudinal sliding movement in a guide 14 located at one end of the frame 10. The opposite end of the bar 12 is provided with a pivotally connected bearing 15 having an elongated slot 15' therein to receive a pin 15a which is anchored to the operating end of a lever 16, the latter being pivoted or hinged to a bracket 17 detachably connected to the frame 10 as best shown in Fig. 4. The handle when in idle position will fold down and nest on the bar 12 and prongs 13, note Figs. 1 and 2. However, when the handle is raised and then retracted to a point where it brings the bar 12 to its extreme retracted position, the free end of said bar clears the guide 14, permitting the said bar to swing clear of the tray and allow the ice blocks in the freezing compartments 11 to fall or be removed from said compartments unimpeded by said bar or lever, note Fig. 3. The elongated bearing slot 15' compensates for the arcuate throw of the operating end of the lever, resulting in a substantially linear or horizontal operating movement of the bar 12.

In operation, assuming it is desired to use the tray or pan 10 for freezing ice cubes, the bracket 17 together with the bar 12 and lever 16 may be mounted on the tray and the compartments 11 filled with water or other fluid to be frozen. As freezing takes place, the downward projecting prongs or fingers 13 become embedded in the ice mass. When it is desired to dislodge the ice, it is only necessary to raise the handle 16, whereupon the prongs 13 are moved rearwardly or toward the left as indicated in Fig. 3, thereby exerting a rotational thrust on the ice blocks in the freezing compartments 11. Due to the relatively great leverage afforded by the operating end of the lever 16, the ice blocks will be subjected to considerable force when the lever is actuated, with a minimum of manual effort. When the bar 12 reaches its retracted position, its free end clears the guide 14, whereupon it may be swung back clear of the tray as in Fig. 3 to permit unimpeded fall by gravity or removal in any other manner of the ice blocks or cubes.

In the event it is desired to use the tray for

ordinary baking purposes, the bracket 17 may be readily removed along with the bar 12 and lever 16. Baking pans of the type herein shown are usually provided with holes in the opposite ends of the frame for hanging the pan from a nail or other suitable member, and these holes facilitate mounting of the bracket 17, as will be noted from Fig. 4. If desired, the guide 14 may be mounted in a similar manner.

It will be understood that certain minor changes in construction and design may be adopted without departing from the spirit or scope of the invention as defined by the appended claims.

What is claimed is:

1. A tray for use in the freezing unit of a refrigerator comprising a frame having a series of spaced rounded freezing compartments therein, an actuator bar extending longitudinally of the tray between said compartments and having a free end slidably connected to the frame and a lever pivotally connected to the opposite end thereof whereby when the lever is actuated the said bar is moved backwardly and forwardly along the frame, and a series of prongs rigidly connected to said bar and projecting downwardly into the freezing compartments to be embedded in the ice mass, said prongs being eccentrically located with respect to the axes of the said freezing compartments.

2. A freezing tray for use in the freezing unit of a domestic refrigerator, comprising a frame having rows of rounded freezing compartments formed therein, an actuator bar disposed on said frame between said rows of compartments, prongs rigidly connected to said bar at spaced points therealong and projecting downwardly into said compartments to be embedded in the ice mass during freezing of the latter, a guide for said bar connected to the one end of said frame, the one end of said bar slidably projecting through said guide, and a lever pivotally connected at its one end to the end of said frame opposite said bar guide, the opposite end of said bar being pivotally connected to said lever adjacent the pivoted end of the latter whereby when the lever is raised and lowered the bar is reciprocated to in turn displace the ice blocks by rotating the latter in their compartments.

3. A tray for use as a freezing unit comprising a frame having a series of rounded cup-shaped compartments arranged in spaced rows, an actuator bar having a series of downwardly projecting prongs rigidly secured at spaced points therealong to be embedded in the ice mass in said compartments, said prongs being eccentrically located with respect to the axes of said compartments, a lever connected to said rod for actuating the latter, and means detachably mounting said rod and lever on said frame for ready separation from the latter to adapt the tray for other purposes.

4. A tray for use as a freezing unit comprising a frame provided with a series of rounded cups arranged in spaced substantially parallel rows, an actuator bar having a series of downwardly projecting prongs rigidly secured at spaced points therealong to be embedded in the ice mass in said cups, a guide for said bar located at one end of said frame and a hinge bracket detachably secured in the opposite end of the frame, and a lever

having one end hinged to said bracket and adapted to fold down on said frame, the one end of said actuator bar being pivotally connected to the hinged end of the lever and the opposite end of said bar being mounted for free sliding movement in said guide.

5. Ice forming apparatus for use in the freezing unit of a refrigerator comprising a tray having a series of rounded freezing compartments therein, an actuator bar mounted on said tray adjacent said compartments and provided with a series of spaced rigid prongs projecting downwardly into said freezing compartments and eccentrically disposed with respect to the axes of said compartments, a guide for said bar located adjacent one end of the bar and an actuating lever for said bar pivotally hinged to the tray adjacent the opposite end of said bar, said bar being pivotally connected to said lever adjacent the hinge point of the latter, said guide being so located as to permit the end of the bar to free itself from the guide when the bar is retracted and permit the bar and lever to be swung clear of the top of the tray.

6. Ice-forming apparatus for use in the freezing unit of a refrigerator comprising a tray having a series of freezing compartments therein, an operating lever hinged to said tray, an actuator bar having its one end pivotally connected to said lever adjacent the hinge point of the latter, a guide for the opposite end of said bar, and means connected to said bar and extending into said compartments to engage the ice mass in the latter, said guide and said bar being so constructed and arranged as to permit the bar to free itself from said guide when the bar is retracted to a predetermined position so that the bar and lever may be swung free of the tray and permit unimpeded removal of ice blocks from said compartments.

7. A tray for use in the freezing unit of a refrigerator comprising a frame having a series of spaced rounded freezing compartments therein, an actuator bar slidably mounted on said tray and extending longitudinally of the latter between said compartments, a guide member located adjacent one end of said bar, a hinge bracket located adjacent the opposite end of said bar, and an operating lever hinged to said bracket, said bar being provided with prongs at spaced points therealong projecting downwardly into said freezing compartments and located eccentrically with respect to the axes of the latter, the one end of said bar being slidably mounted in said guide and the opposite end of said bar being pivotally connected to said lever adjacent the hinge point of the latter, said lever being provided with an elongated bearing slot for the pivotal connection of said bar to compensate for arcuate movement of the lever and permit substantially linear reciprocation of said bar.

8. A freezing tray for use in the freezing unit of a domestic refrigerator comprising a muffin pan and ice-dislodging means including an actuator bar and an operating lever therefor detachably connected to said pan, said bar being provided with rigid prongs projecting downwardly into the muffin compartments of the pan and eccentrically disposed with respect to the axes of the latter.
